UNITED STATES PATENT OFFICE.

FRANCIS A. DEVEREAUX, OF INTERNATIONAL FALLS, MINNESOTA, ASSIGNOR OF ONE-FOURTH TO FRANK H. KEYES AND ONE-HALF TO HERMAN KOENEKE, BOTH OF INTERNATIONAL FALLS, MINNESOTA.

PIPE-WRENCH.

1,354,538.

Specification of Letters Patent.

Patented Oct. 5, 1920.

Application filed September 13, 1919. Serial No. 323,481.

To all whom it may concern:

Be it known that I, FRANCIS A. DEVEREAUX, a citizen of the United States, residing at International Falls, in the county 5 of Koochiching and State of Minnesota, have invented certain new and useful Improvements in Pipe-Wrenches; and I do hereby declare the following to be a full, clear, and exact description of the invention, such as will enable others skilled in the art to which it appertains to make and use the same.

My invention has for its object to provide an improved internal pipe wrench 15 adapted to work in the interior of a pipe, and to do this when rotating in either direction. Generally stated, the invention consists of the novel construction and combination of parts hereinafter described and 20 defined in the claims.

The improved wrench is illustrated in the accompanying drawings wherein like characters indicate like parts throughout the several views. Referring to the drawings:—

Figure 1 is a view in side elevation showing the improved wrench;

Fig. 2 is a section taken approximately on the line 2—2 of Fig. 1;

Fig. 2^a is a detail view showing one of the interchangeably usable dogs removed from position;

Fig. 3 is a section on the same line as Fig. 2, but showing the wrench applied inside of the pipe or tube; and

Fig. 4 is a view corresponding to Fig. 3, but showing the wrench operating in a reverse direction.

In Figs. 3 and 4, the pipe is indicated 40 by the numeral 5. The wrench comprises a handle 6 having a laterally offset head 7. This head 7, near its end, is formed with a large transverse notch 8 which leaves the extreme outer end of the head connected to 45 the body thereof only by a neck portion 9, which is preferably made approximately V-shape in cross section. At a point diametrically opposite to the neck 9, a small pivot or large pivot pin 10 is inserted through 50 alined seats in the inner and outer portions of the head at a point eccentric to the axis of said head. This pivot pin 10 is endwise removable but is normally held in position by a screw 11 applied to the outer portion

of the head and engageable with said pin. 55 Pivoted on the exposed intermediate portion of the pin 10 is a dog 12 provided with one or more sharp teeth at its free end. Preferably, said dog has one large intermediate tooth 12^a and on each side thereof, 60 a short tooth 12^b. This dog will be normally pressed outward by one or the other of two oppositely acting torsion springs 13. These torsion springs are alike, except one is a right hand and the other a left hand 65 spring. Each spring is coiled about, or at least part way around the pin 10. Each spring has an end 13^a anchored in the outer portion of the head 7, and a free end portion 13^b that is engageable with the dog 12. 70

Of course, this wrench will act only upon pipes, the interiors of which are of slightly larger diameter than the exterior of the head 7, but the pipes may be considerably larger than the said head 7. Moreover, to 75 extend the range of action of the wrench to pipes that are of very much greater diameter than the said head 7, I provide interchangeably usable dogs 12 of different length.

In Fig. 2^a, for example, there is shown a dog that is much longer than those of the other views, and which may be interchanged with the short lugs, at will.

Fig. 3 illustrates the wrench applied to 85 rotate the pipe in a clockwise direction and Fig. 4 shows the wrench applied to rotate the pipe in an anti-clockwise direction. It will be noted that in both actions of the wrench, the dog is yieldingly pressed outward by one or the other of the springs 13, so that its sharp edge will maintain engagement with the pipe when the wrench is given a backward rotation and will grip the pipe when rotating in a forward direction. Also, it is evident that the greater the force applied to the lever 6 required to rotate the pipe, the greater will be the gripping action of the dog and wrench head on the interior of the pipe.

This improved wrench may be made at reasonably small cost, is of extremely simple construction and is highly efficient for the purposes had in view.

What I claim is:

1. An internal pipe wrench comprising a head insertible into the pipe, the said head having a notch and an eccentric pivot pin

- extending into said notch, and a dog pivoted on said pivot pin for movement from one side to the other of a line that intersects the axis of the head and pivot pin.
5. An internal pipe wrench comprising a head insertible into the pipe, the said head having a notch and an eccentric pivot pin extending into said notch, and a dog pivoted on said pivot pin for movement from one side to the other of a line that intersects the axis of the head and pivot pin, the said dog being operative under rotation of said head in either direction.
10. An internal pipe wrench comprising a head insertible into the pipe, the said head having a notch and an eccentric pivot pin extending into said notch, a dog pivoted on said pivot pin for movement from one side to the other of a line that intersects the axis of the head and pivot pin, and a spring anchored in respect to said head and operative on said dog to yieldingly hold the same in working position.
15. An internal pipe wrench comprising a head insertible into the pipe, the said head having a notch and a pivot pin extending into said notch, a dog pivoted on said pivot pin, the said dog being operative under rotation of said head in either direction, and reversely acting spring means anchored to said head and operative on said dog to hold the same in either of its two working positions.
20. An internal pipe wrench comprising a head insertible into the pipe, the said head having a notch and a pivot pin extending into said notch, and a dog pivoted on said pivot pin, the said dog being operative under rotation of said head in either direction, and reversely acting spring prongs anchored to said head and pin and having reversely projected spring prongs with one of which spring prongs, said dog is engageable, according to the direction into which it is turned for action.
25. An internal pipe wrench comprising a cylindrical head having near its end a large notch leaving the outer portion of the head connected with the body of the head only by a connecting neck at one side of the head, a pivot pin insertible through seats in said head at a point diametrically opposite said neck, a dog pivoted on said pin and working within said notch, and reversely acting spring prongs anchored to said head and looped about said pin with their ends projecting in opposite directions for action on said dog, according to the direction in which said dog is turned for action.
30. An internal pipe wrench comprising a head insertible into the pipe, the said head having a notch and a pivot pin extending into said notch, and a dog pivoted on said pivot pin, the said dog being operative under rotation of said head in either direction, and reversely acting spring prongs anchored to said head and pin and having reversely projected spring prongs with one of which spring prongs, said dog is engageable, according to the direction into which it is turned for action.

In testimony whereof I affix my signature in presence of two witnesses.

FRANCIS A. DEVEREAUX.
